(No Model.)

W. H. DE CAMP.
COMBINED CHURN AND ICE CREAM FREEZER.

No. 553,554.

Patented Jan. 28, 1896.

Fig. 1.

UNITED STATES PATENT OFFICE.

WILLIAM H. DE CAMP, OF FORT WAYNE, INDIANA.

COMBINED CHURN AND ICE-CREAM FREEZER.

SPECIFICATION forming part of Letters Patent No. 553,554, dated January 28, 1896.

Application filed May 22, 1895. Serial No. 550,230. (No model.)

To all whom it may concern:

Be it known that I, WILLIAM H. DE CAMP, a citizen of the United States, residing at Fort Wayne, in the county of Allen, in the State of Indiana, have invented certain new and useful Improvements in a Combined Churn and Ice-Cream Freezer; and I do hereby declare that the following is a full, clear, and exact description of the invention, which will enable others skilled in the art to which it appertains to make and use the same, reference being had to the accompanying drawings, which form part of this specification.

My invention relates to improvements in a combined churn and ice-cream freezer.

The objects of my invention are to produce a convenient and economical machine which can be used both as a common dairy or household churn and a cream-freezer. I attain these objects by the mechanism illustrated in the accompanying drawings, in which—

Figure 1 is a vertical sectional view of the entire machine; and Fig. 2 is a detail partly-sectional view of pinion 9, with a section of the wire agitator 10.

Similar figures refer to similar parts throughout the several views.

1 is a platform or table securely fastened to and supported by any proper number of legs 18 so as to give the necessary stability and strength to sustain the other parts of the machine. If desired, the legs can be secured to the floor by screws or bolts through the flanges 35.

31 is a shelf securely fastened to the legs 18 at a sufficient distance beneath the table 1 to receive and support the machine thereon, as hereinafter described.

24 is a bed-plate casting resting upon the shelf 31 and rigidly secured to it by any suitable means.

23 is a conical bearing in the casting 24 and in which rests the conical end of a vertical cylindrical rotatable shaft 5, which extends nearly to the top of the machine, as herein-after described.

Rigidly secured to the lower end of the shaft 5, just above its bearing, is a bevel gear-wheel 22, and at a proper distance above the gear-wheel is a collar 20, also rigidly secured to the shaft 5. Resting upon the upper side of the collar 20 and sleeved upon 5 is a ver-

tical, hollow, cylindrical, and rotatable metallic shaft 2. At the lower end of the shaft 2 is rigidly secured another bevel gear-wheel 19. 55

25 and 25 are vertical standards integral with the casting 24, and having at the upper ends boxes in which are journaled the horizontal cylindrical shaft 26. At the outer end of 26 is secured a removable crank 27 and at 60 the inner end is rigidly secured the bevel gear-wheel 21, which meshes on its lower side with the wheel 22 and on its upper side with the wheel 19.

The shaft 2 passes through a perforation in 65 the table 1 and through a suitable box-bearing 17 secured upon the upper surface of said table. At a suitable distance above the table 1 to admit of free movement there is rigidly secured to the shaft 2 a horizontal, circular, and centrally-perforated metallic plate 36, which will rotate with the shaft 2, as hereinafter stated. From its lower end to the upper surface of the plate 36 the shaft 2 is of uniform diameter; but the part 6 above the 75 plate is conical and extends nearly to the top of the churn-body 3.

Resting upon the plate 36 and supported by it is a metallic cylindrical flat-bottomed churn-body 3 having in its diametrical center 80 a conical thimble 16 corresponding to the perforated plate 36 and which surrounds the shaft 2 and is open at both ends. This thimble 16 extends nearly to the top of the churn 3 and is integral with its bottom so as to securely retain the contents within the churn when charged. 85

Above the upper end of the thimble 16 a horizontal spur-gear wheel 8 is removably secured to the upper end of the shaft 2 so as 90 to revolve with the shaft.

Above the wheel 8 upon the shaft 5, and removably secured to it, is a horizontal lever 7, with arms of unequal length extending from its attachments with the shaft 5. At 95 the end of the longer arm of 7 is attached, obliquely to the radius of 5, a scraper 11, with its outer edge just in contact with the interior sides of the churn 3. To the shorter arm of 7 is removably attached the spur-pinion 9 by a bolt and washer 43, as shown in Fig. 1.

In the pinion 9 are perforations for the wires, which collectively form the agitator 10

and which are attached and arranged as shown in the detail view, Fig. 2. The pinion 9 is geared with the spur-wheel 8, and revolves freely upon its journal 43.

5 The churn-body 3 has a removable lid 4, which can be secured by suitable clamps 15.

13 is a removable ice-tub having suitable handles 14 and in its center a concentric opening for the plate 36 and the churn 3. 12 is 10 an interior concentric jacket forming the circumference of the said opening, and is made of non-corrosive metal and integral with the bottom 37 of the ice-tub. This jacket is about one-third in height of the outer wall of the tub, 15 and both the plate 36 and the churn 3 fit closely within the opening, but sufficiently loose to permit both plate and churn to rotate freely with the shaft 2. By this construction an annular space for the freezing mixture surrounds 20 the churn and permitting contact with it is formed.

A motor attachment for operating the machine is shown in Fig. 1, which may be attached and thereby much manual labor be dispensed with, which I describe as follows: Vertical upright metallic standards 42 are rigidly secured to the casting 24 at one side of the standards 25. Upon the standards 42 is mounted a horizontal shaft 41, at the outer 25 end of which is attached a suitable operating-crank 33, and at the other extremity are mounted upon said shaft a spur-gear wheel 38 and a coiled steel spring 29, having its upper end rigidly secured to a cross-bar rigidly 30 attached to the standards 42. A rotatable shaft 40 is also mounted upon the standards 42, upon which is a pinion-wheel 39, which meshes into 38, and also a pinion 30, which meshes into the spur-wheel 28, mounted upon 35 the shaft 26. By means of the crank 33 the spring 29 can be wound up like a clock-spring, and its expansive force will produce a rotary motion to the churn through the driving-wheel 21.

40 Other suitable methods of applying motive power will be suggested to mechanics.

The method of operating my invention is as follows: To use as a churn the milk or cream is placed in the churn 3 without filling 45 it quite to the upper end of the sleeve 16. The lid 4 is secured in place, and by turning the crank 27 motion is communicated to the shafts 2 and 5. It is obvious that the shafts will revolve in opposite directions and that 50 the agitator 10 will revolve about the shaft 2 and at the same time rotate upon its own axis, while the scraper 11 will revolve upon the shaft 5. The churn 3, mounted upon the plate 36, will also revolve, and by these opposite motions the contents of the churn will be thoroughly agitated and the milk speedily converted into butter and whey. The scraper 55 while preventing accumulation of the butter on the side of the churn will constantly force 60 the contents toward the agitator 10.

The method of removing the contents will

be so readily understood as not to need a detailed description.

For use as a freezer the material is placed in the churn and the space between 3 and 13 70 filled with the freezing mixture, as in other freezers. The rotatory motion of the churn brings its sides in immediate contact with the freezing mixture at all points, while the cream or other contents to be frozen are thoroughly 75 stirred by the agitator 10 and the scraper 11.

Having thus described my invention, what I claim, and desire to secure by Letters Patent, is—

1. A churn having a metallic circular churn body 3, a flat bottom and a conical thimble 16 centrally located and integrally attached thereto as shown; a removable lid 4 adapted to be secured to the churn body and secured thereon by suitable means; a table 1 centrally perforated and mounted upon suitable legs and having a shelf 31 secured to said legs; a plate casting 24 having vertical integral standards 25 and a bearing 23; a rotatable metallic shaft 5 resting at its lower end in the bearing 23 and having a bevel gear wheel 22; a hollow rotatable shaft 2 having a metallic plate 36 rigidly secured to it above the table 1; a removable spur wheel 8 secured to the upper end of shaft 2; a removable arm 7 secured to the upper end of the shaft 5 and having at the extremity of its longer arm a scraper 11, and at the extremity of its shorter arm a rotatable agitator 10 and pinion 9 adapted to mesh with the spur wheels 8; a horizontal, rotatable shaft 100 26 journaled in the vertical standards 25 and a bevel geared wheel secured therein adapted to mesh with the wheels 19 and 22 as shown for the purposes stated.

2. A churn and cream freezer comprised of 105 a circular churn body 3 having a flat bottom, a conical thimble 16 centrally located in said churn body and integrally a part of the same; a removable lid adapted to be secured to said churn body by suitable means; a table centrally perforated and mounted upon suitable legs and having a shelf 31 secured to said legs; a plate casting 24, having vertical integral standards 25 and a bearing 23; a vertical, rotatable metallic shaft 5 resting at its lower 110 end in the bearing 23 and having a bevel gear wheel 22; a hollow rotatable shaft 21 having a metallic plate 36 rigidly secured to it above the table 1; a removable gear wheel 8 secured to the upper end of the shaft 2; a removable arm 7 secured to the upper end of the shaft 5 and at the extremity of its longer arm a scraper 11 and at the extremity of its shorter arm a rotatable agitator 10 and pinion 9 adapted 115 to mesh with the spur wheel 8; a horizontal shaft 26 journaled in the vertical standards 25, and a bevel geared wheel secured thereto adapted to mesh with the wheels 19 and 22 as shown; a removable ice tub having in its center a concentric opening for the 120 plate 36 and the churn body 3; an interior concentric jacket of non corrosive metal and

integral with the bottom of the ice tub, substantially as shown and described and for the purpose stated.

3. The combination of a cylindrical churn body removably fixed upon a revolving support as shown and provided with a thimble for the supporting shaft: a vertical tubular shaft rotatably mounted in said thimble and provided near its lower end with an integral 10 disk for supporting said churn body and having upon its lower extremity a rigid bevel gear wheel meshing with an actuating gear wheel as shown, and provided upon its upper end with a horizontal gear wheel meshing with a 15 pinion on the rotatable agitator; a vertical shaft 5 rotatably mounted in a proper sup-

port as shown; a rigid gear bevel meshing with the said actuating gear and having upon its upper end a fixed horizontal arm, carrying upon one extremity, a fixed scraper, for the 20 purpose specified, and upon the other extremity a rotatable agitator, actuated by a meshing pinion as described, and proper means for simultaneously actuating the said bevel gears, all substantially as described and shown 25 and for the purpose specified.

Signed by me, at Fort Wayne, Indiana, this 14th day of May, 1895.

WILLIAM H. DE CAMP.
